(57) **CLAIM**

The ornamental design for a battery, as shown and described.

DESCRIPTION

FIG. 1 is a top, front, left perspective view of a battery; FIG. 2 is a top, rear, left perspective view of the battery of FIG. 1;

FIG. 3 is a front elevational view of the battery of FIG. 1; FIG. 4 is a rear elevational view of the battery of FIG. 1; FIG. 5 is a right side elevational view of the battery of FIG. 1;

FIG. 6 is a top plan view of the battery of FIG. 1; FIG. 7 is a top, front, left perspective view of a battery; FIG. 8 is a top, rear, left perspective of the battery of FIG. 7;

FIG. 9 is a front elevational view of the battery of FIG. 7; FIG. 10 is a rear elevational view of the battery of FIG. 7; FIG. 11 is a right side elevational view of the battery of FIG. 7; and,

FIG. 12 is a top plan view of the battery of FIG. 7. The broken lines in the drawings are for the purpose of illustrating portions of the article that form no part of the claimed design. Bottom views have been omitted as the bottom surfaces are flat and devoid of surface ornamentation.

1 Claim, 12 Drawing Sheets
